Primary Examiner — Ricky Pham*(74) Attorney, Agent, or Firm* — Notaro, Michalos & Zaccaria P.C.(57) **CLAIM**

The ornamental design for a stackable piece of cookware, as shown and described.

DESCRIPTION

FIG. 1 is a top, rear, right perspective view showing my design therefor;

FIG. 2 is a front, top perspective view thereof;

FIG. 3 is a right side elevational view thereof;

FIG. 4 is a rear elevational view thereof;

FIG. 5 is a front elevational view thereof;

FIG. 6 is a top plan view thereof;

FIG. 7 is a bottom plan view thereof; and,

FIG. 8 is a sectional view taken along the line 8-8 of FIG. 3.

The broken lines are for the purpose of illustrating portions of the article that form no part of the claim.
